UNITED STATES PATENT OFFICE.

ERWIN C. BAUMGRAS, OF WASHINGTON, DISTRICT OF COLUMBIA, ASSIGNOR
TO JACOBS BROTHERS, OF SAME PLACE.

DESIGN FOR A SPOON.

SPECIFICATION forming part of Design No. 20,655, dated March 31, 1891.

Application filed March 9, 1891. Serial No. 384,362. Term of patent 3½ years.

To all whom it may concern:

Be it known that I, ERWIN C. BAUMGRAS, a citizen of the United States, residing at the city of Washington, in the District of Columbia, have invented and produced a new and original Design for a National Souvenir Spoon, of which the following is a specification, reference being had to the accompanying drawing, forming a part thereof.

10 The leading features of my design consist in the handle, which for its full length represents a cannon, around which is intertwined a floral wreath. Springing from the cannon-handle is the bowl, upon the lower

end of which is displayed the heraldic shield 15 of the United States, overlying which are two crossed swords. Above the representation of the stars and stripes the bowl of the spoon is left plain for such additional ornamentation as taste may dictate. 20

What I claim is—

The design for a spoon herein described, and illustrated in the drawing.

ERWIN C. BAUMGRAS.
